(57) **CLAIM**

The ornamental design for a plate carrier, as shown and described.

DESCRIPTION

FIG. 1 is a perspective view of a plate carrier, showing my new design;

FIG. 2 is a front elevational view thereof, the rear elevational view being a mirror image thereof;

FIG. 3 is a top view thereof;

FIG. 4 is a bottom view thereof; and,

FIG. 5 is a left side elevational view thereof, the right side elevation view being a mirror image thereof.
